UNITED STATES PATENT OFFICE.

FREDERICK A. STEVENS, OF PROVIDENCE, RHODE ISLAND.

DESIGN FOR A CLAMP FOR RIMLESS SPECTACLES.

SPECIFICATION forming part of Design No. 33,278, dated October 2, 1900.

Application filed August 31, 1900. Serial No. 28,715. Term of patent 14 years.

To all whom it may concern:

Be it known that I, FREDERICK A. STEVENS, a citizen of the United States, residing at Providence, in the county of Providence and State of Rhode Island, have invented and produced a new and original Design for a Clamp for Rimless Spectacles, of which the following is a specification, reference being had to the accompanying drawings, forming part thereof.

Figure 1 is a side view of a clamp for rimless spectacles, showing my new design. Fig. 2 is an end view of the same. Fig. 3 is a sectional view on the line X X of Fig. 1. Fig. 4 is a view at right angles to the view of Fig. 1. Fig. 5 is a sectional view on the line Y Y of Fig. 4.

The article shown in the drawings is used on rimless spectacles and secured to the lens by a pin extending through the holes in the arms *a a* and the lens, the arm *b* bearing on the peripheral edge of the lens.

As shown in the drawings, the leading or material feature of my design consists of the arched central portion of the arm *b*, as shown

in Fig. 5, the inner surface of the central portion forming a section of a circle the center of which is located in the hole of the arm *a*. The two arms *a a* are parallel to each other and have at their ends enlarged rounded ends 30 pierced with central holes. The arm *b* extends in a general curve beyond the opposite sides of the arms *a a*, which unite with the arm *b* by a short bend. The central portion of the arm *b* forms an arch of which the holes 35 in the arms *a a* are the center.

Having thus described my invention, what I claim as new, and desire to secure by Letters Patent, is—

The design for a clamp for rimless spectacles substantially as herein shown and described.

In testimony whereof I have signed my name to this specification in the presence of two subscribing witnesses.

FREDERICK A. STEVENS.
